SEAR MECHANISM

Giulio Sosso, Turin, Italy

Application April 10, 1937, Serial No. 136,079
In Italy April 14, 1936

1 Claim. (Cl. 42—69)

This invention relates generally to sear mechanism comprising a trigger and pawl for automatic fire arms, more particularly automatic pistols, and it has for its object certain improvements relating to the sear and trigger mechanism, the most important of such improvements consisting in providing means to permit re-cocking of the hammer by pulling the trigger.

The accompanying drawings show a construction of the object of this invention in connection with an automatic pistol of the recoiling barrel type.

Figures 1 and 2 show partly in section the weapon with the trigger and hammer in their released position, and partly drawn-back trigger and cocked hammer ready for firing.

Figure 3 shows the weapon directly after firing and before it takes the position shown in Figure 2.

Figure 4 shows diagrammatically the automatic safety device.

Finally Figures 5, 6, 7 and 8 are enlarged fragmentary views of the trigger and hammer mechanism illustrating in greater detail the relative positions of the parts during various stages of operation.

Throughout the views the same reference numerals indicate the same or like parts.

The frame 1 of the weapon comprises the half 2, trigger guard and the chamber for the magazine, which in the example shown is of the curved endless belt type according to my copending application Ser. No. 82,695 filed on June 1, 1936. The breech bolt 3 is slidably fitted in the frame and extends to the further end of the barrel 4 contained in the breech bolt. The barrel is guided in front in the bush 5 mounted by a bayonet joint in the breech bolt and rests at its rear end on a larger cross pin 6 in the frame by means of the breech 7 of the barrel, engaging by means of two teeth after the manner of a rack with a set of teeth on the pin 6. A sleeve 8 is fitted on the barrel and is held against the breech 7 by means of the spring 9 stretched between the breech 7 and bush 5. The sleeve 8 is provided with two cross bolts 8a pressed in a direction opposite to the pressure of the spring 9 on the sleeve by a fork 10 pivoted to the frame at 10a. The hammer 11 is pivoted to the back of the frame at 11a. The hammer is connected to the fork 10 by means of the link 12, so that on oscillation of either of them in one direction, the other oscillates in the opposite direction.

A tooth 15 having an abutment 15a is articulated to the fork.

A pawl 14 rockably mounted on the trigger 13 pivoted to the frame at 13a cooperates with the abutment 15a of the rocking tooth 15 on the fork 10. A spring 16 seated in a recess in the trigger acts on the rear end of the pawl 14.

The pin 6 which is operatively connected with the barrel through the teeth on the breech 7, is further operatively connected with the breech bolt 3 by means of an arm 17, shown in dotted lines in Figures 1 to 3, which is solidly fixed to the pin 6 and engages into a recess in the breech bolt. The barrel and breech bolt are thereby operatively connected together, and as the barrel recoils by a small extent, by reason of the engagement of the sets of teeth it rocks the arm 17 which pushes the breech bolt backwardly compressing the spring 9 by the proper extent for introducing the fresh bullet into the barrel and cocking the hammer.

The extractor 18 is pivoted as usual to the breech bolt by its extensions 18a and retains the striker 19 which is provided with a damping spring 20.

The weapon is provided with an automatic safety device maintaining the striker locked until the trigger is drawn back. This safety device consists of a cross member 22 (Figure 4) pushed by a spring 23 into the path of the striker for locking it. The cross member is formed at its 30 end remote from the spring with an incline 22a along which the push rod 24 may slide under the action of the trigger as the latter is depressed (Figures 2 and 3), moving the cross member against the action of the spring 23. The cross member has a notch 22b which in the depressed position of the trigger comes underneath the striker permitting movement thereof. When the trigger is inoperative, the striker is locked and in its safety position, from which it is automatically released on depression of the trigger.

The weapon is loaded as usual by pulling the breech bolt which has a milled rear end. A spring controlled pawl 21 is provided in the frame and has a knob 21a and nose 21b which is engaged by a mortise 3' in the breech bolt and holds the latter in its backward position for easy inspection of the weapon.

By pulling the breech bolt 3 backward, the hammer 11 is cocked and by rocking backward it oscillates the fork 10 forward by means of the link 12, said fork cocking the spring 9 by means of the sleeve 8. The hammer remains in the cocked position as the breech bolt turns forward to its normal position by the fact that the 55 forward oscillation of the fork 10 has permitted

the oscillating tooth 15 to become engaged with the stop 15b on the frame, as shown in Figure 2.

The weapon is ready for firing, but the striker is as yet locked by the cross member 22 because the spring 16 still pushes the trigger 13 forward.

On drawing back the trigger, at first the pawl 14 comes into contact with the abutment 15a on the tooth 15, should this not yet have taken place, slightly compressing the spring 16, and the striker is released from the cross member (Figure 2). To fire the shot the trigger is drawn back a little further, now releasing the tooth 15 from the stop 15b and successively, the pawl 14 becomes disengaged from the tooth 15, for the rear portion of tooth 15 is raised during the rocking movement thereof by effect of the pawl and, upon reaching a certain position, the pawl 14 slips above the abutment 15a on the tooth 15. In this manner, the fork 10 is set free, so that the hammer connected to the fork 20 by the link 12 may now freely be actuated by the spring 9.

When the shot has been fired, the barrel recoils by a few millimeters while the breech bolt thrown by the arm 17 performs a long stroke (Figure 3) necessary for introducing the fresh bullet into the barrel and re-cocking the hammer, whereupon the arm takes again the position shown in Figure 2 as soon as the trigger 13 is released.

At this moment the spring 16 pushes the trigger 13 forward bringing the tip of the pawl 14 again opposite the abutment 15a on the tooth 15. The weapon is now ready for firing a new shot, unless the hammer is lowered by hand, in which case it is returned to the position of Figure 1 upon exerting a very slight pressure on the trigger 13 for releasing the tooth 15 from the abutment 15b.

When after such releasing of the hammer by hand, the trigger 13 is pulled, the tip of pawl 14 abuts the shoulder or abutment 15a or pawl 15. On further movement of the trigger, the fork or sear member 10 is oscillated and thus the hammer is re-cocked through the link 12. 45 During these displacements the pawl 15 oscillates on its pivot on the fork 10 and after the hammer has been re-cocked the pawl tip, during the further movement of the trigger, is disengaged from the shoulder 15a. The fork is therefore free to oscillate backwards under the action of the spring 9, thus oscillating the hammer forward and firing the shot.

If we refer more particularly to Figure 5, the normal inoperative conditions and positions of 55 the various parts of the sear mechanism are shown.

In other words, the main spring 9 is shown extended, the hammer 11 is on the breech bolt, the pawl 15 has passed over the abutment 15b, the trigger has been returned outwards into the normal inoperative position pushed by the spring 16 and the end of the pawl 14 is in engagement with the notch 15a of pawl 15.

Assuming that the hammer 11 (Figure 6) is 65 to be brought to the cocked position, this operation can be effected in two different ways. For example, if the firearm has not yet been loaded, that is to say if the cartridge has not yet been introduced into the barrel, the breech bolt is pulled back by hand. Through this movement, the breech bolt, on striking the hammer, carries it into the cocked position and compresses, by means of the link 12, the main spring 9 and at the same time, by the anticlockwise oscillation 70 its free end against the upper face of the first

of the fork sear member 10, the pawl 15 is brought behind the abutment 15b assisted in this movement by the spring 16. On the return movement the breech bolt introduces the cartridge into the barrel; during this movement the hammer is locked by engagement of pawl 15 on the abutment 15b.

On the other hand, if the firearm is already loaded, the trigger is pulled back by this movement, a counter-clockwise movement is imparted 10 to the fork sear member through the pawl 14 in engagement with the notch 15a and the pawl 15, so that cocking of hammer 11 and compression of the main spring 9 are started. As soon as the end of pawl 15 is disposed behind the abutment 15b, its spring 16, through pawl 14, causes pawl 15 to oscillate in a clockwise direction, throwing it into engagement with the abutment 15b. If at this moment the trigger is released, the hammer remains in the cocked position.

If firing is intended to take place (Figure 7), the trigger 13 is pulled out further thus causing the fork sear member 10 to effect a counter-clockwise rotation so as to bring the hammer into the full cocked position, and on further compressing the main spring 9 the pawl 15 is released from the abutment 15b.

By this further counter-clockwise rotation of 30 the fork sear member 10, the pawl 15, which has been rotated on the pin of the fork sear member 10 has reached such a position as to permit the end of the pawl 14 to slide (by effect of the pull on the trigger 13) on the inclined surface of the notch 15b, releasing it from the latter (Figure 8).

As soon as this takes place, the fork sear member 10 which is no longer retained by the trigger, by a snapping movement produced by the extension of the main spring 9, effects a clockwise rotation causing the hammer 11 to snap on the striker 19 for firing. During the firing movement the pawl 15, due to the sliding of the end of pawl 14 on the surface above its oscillation pin, cannot effect a clockwise rotation and therefore passes over the abutment and allows the hammer to perform its stroke. Upon, thereafter releasing the trigger 13, the parts are returned into the position shown in Figure 4, that is to say the pawl 14 is returned by the spring 16 into the notch 15a.

The constructional details, type of weapon, method of loading, etc., may be largely varied from what has been described and shown by way of example without departing from the scope of this invention.

What I claim is:

Sear mechanism for pistols, comprising a frame, a movable hammer on the frame capable of being cocked, a barrel, a main spring surrounding a barrel, a fork sear member journaled on the frame and coacting with said main spring, a link connecting the hammer to the fork sear member, so that when the hammer oscillates in the cocking direction, the fork sear member oscillates in the opposite direction to compress the main spring, a pawl journaled on the fork sear member and adapted to engage an abutment on said frame when the hammer is brought into the cocking position and the main spring is compressed, a trigger, a second pawl journaled on said trigger, a second spring mounted on said trigger and acting on the second pawl to press 70 its free end against the upper face of the first

pawl, the latter having an abutment coacting with said second pawl to bring the hammer into the cocked position and compress the main spring and also bring the first pawl into engagement with the abutment during the first part of the movement of the trigger, while the last part of the movement of the trigger produces first the

disengagement of the first pawl from the abutment and then the release of the second pawl from the abutment on the first pawl in order to release the main spring and operate the hammer.

GIULIO SOSSO.
